UNITED STATES PATENT OFFICE.

ROBERT DAVID MAYO, OF CLEVELAND, OHIO.

TOILET-SEAT-DISINFECTING MEANS.

1,132,204.

Specification of Letters Patent. Patented Mar. 16, 1915.

Application filed May 21, 1914. Serial No. 889,988.

To all whom it may concern:

Be it known that I, ROBERT DAVID MAYO, a citizen of the United States, and a resident of Cleveland, in the county of Cuyahoga and State of Ohio, have invented a certain new and useful Toilet-Seat-Disinfecting Means; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates particularly to means for disinfecting toilet-seats, but is not restricted to such use as it may be used in any connection for which it is adapted or appropriate.

An object of my invention is the provision of improved means for disinfecting toilet-seats after use, which means is simple and efficient in its construction and automatically operable.

A further object of the invention is the provision of simple and efficient means which is automatically operable by a movement of the toilet seat to permit the discharge of a predetermined quantity of a disinfecting or antiseptic material in liquid or other suitable form in a suitable position to disinfect the toilet seat when in raised position.

Further objects and advantages of the invention will be apparent from the following detailed description thereof.

The invention is fully described in the following specification, and while, in its broader aspect, it is capable of embodiment in numerous forms, a preferred embodiment thereof is illustrated in the accompanying drawings, in which,—

Figure 1 is a side elevation of an apparatus embodying my invention with the seat raised and with parts in section. Fig. 2 is a front elevation thereof with the toilet bowl in section, and Fig. 3 is an enlarged sectional detail of a portion of the discharge means for the disinfecting material.

Referring to the drawings, 1 designates a closet bowl, 2 the customary flushing tank, which is in connection with the bowl, and 3 the toilet-seat which seat has its hinge member 4 pivotally carried by a bracket 5 that is mounted in any suitable manner on the upper rear portion of the bowl. A disinfect-

ing case 6, of rectangular or other suitable form, is secured to the front side of the tank 2 or it may be secured to a wall or other suitable support at the rear of the bowl if the flushing-tank 2 is not in convenient position to support the same. The case 6 is provided in its front side with an opening 7 corresponding in shape to the face or top side of the toilet seat and disposed in proper position for such side of the toilet seat to fit therein when in raised position, as shown in the drawings. The panel 8, which forms the portion of the case front within the opening for the seat 2 when raised is rigidly connected to the back of the case 6 by bolts 9 or in any other suitable manner. The front side of the panel 8, if desired, may be faced with upholstering 10 to form a soft back rest.

The inner and outer walls of the case opening 7 are preferably inwardly flanged, as indicated at 11, and a plate 12 conforming in shape to the shape of the opening 7 is movably carried within the case by a cross-bar 13 and adapted to seat against the inner edges of the respective flanges 11 to close the communication between the interior of the case and the atmosphere when the toilet seat is not positioned in the opening. A rod or shaft 14 is centrally disposed within the case 6 and extends from the panel 8 to the rear side of the case, being mounted at its ends in any suitable manner to such parts. The cross-bar 13 which carries the closure plate 12 is mounted for axial shifting movements on the shaft or rod 14 and is yieldingly urged by a coiled compression spring 15 to move toward the rear of the case and to hold the plate 12 in open position with respect to the opening 7, said spring being interposed between the panel 8 and cross-bar, as shown. A slide collar 16 is mounted for axial shifting movements on the shaft 14 at the rear of the cross-bar 13 and has connection through the medium of a pair of links 17 with a vertically movable control rod 18. Upon an upward movement of the control rod 18 the links 17 are moved from inclined to substantially horizontal position and effect a forward movement of the collar 16 and a consequent forward movement of the cross-bar 13 and plate 12 to close the opening 7 due to the coaction of said collar with the cross-bar. It is preferable to provide a coiled compression spring 19 between the collar 16 and cross-bar 13 to serve to yield-

ingly space said members and to urge the collar to the rear.

In order that the raising movements of the rod 18 may be automatically controlled upon a lowering of the toilet seat 3, the hinge plate 4 is provided with a finger 20, which, upon a lowering of the seat coacts with a block or finger 21 on the lower end of the rod 18 below the case 6 to impart an upward movement to such rod. It is thus evident that the plate 12 normally stands in open position with relation to the seat receiving opening 7 due to the action of the spring 15 thereagainst, and that a lowering 15 of the seat 3 communicates a closing movement to said plate.

In order that the seat 3 may be automatically raised from its reclining position when a downward pressure is removed therefrom, I provide springs 22 in connection with the hinge members of the seat, which springs are adapted to resist a lowering of the seat and to urge a movement of the seat from reclining to upright position.

25 Mounted above the case 6, or in other convenient position, is a container 23 for a disinfecting or antiseptic material preferably of liquid form, such container, in the present instance, being in the form of an inverted 30 bottle with the neck seating against a gasket 24 in the bottom of a case or inclosing member 25 for the container. The gasket 24, in the present instance, is disposed within a pan-like receptacle 26 and extending down 35 from this receptacle with its upper end in communication with the interior of the container 23 is a tube 27, which is provided intermediate its ends with an enlargement forming a chamber 28, in the present instance, of annular form. A valve tube 29 is mounted for longitudinal reciprocatory 40 movements in the tube 27 and has its upper end closed and marginally flanged, as shown at 30, to closely seat against the upper end of the tube 27 to close the communication 45 between such tube and the interior of the container 23. A coiled compression spring 31 encircles the lower end of the tube 29 between a collar 32 thereon and the lower end 50 of the tube 27 and urges a downward or seating movement of the valve tube. The tube 29 is provided with an interior partition 33, which divides the tube into upper and lower compartments, the upper compartment 34 55 of which may be termed the measuring compartment for each charge of disinfecting material which is to be admitted into the case 6 from the container 23, as hereinafter described. The partition 33 is so disposed 60 that it will stand below the upper end of the chamber 28 when the valve tube is in its lowered or seated position, as shown in Fig. 3, and will move above the upper end of said chamber when the valve-tube is raised. Upon a raising of the valve-tube

from its normal seated position, a plurality of openings 35 in the upper end portion thereof are uncovered to the interior of the container 23 to permit liquid from such container to enter and fill the measuring compartment 34 of the valve. Upon a lowering of the valve to its normal seated position, a plurality of openings 36 are uncovered to the interior of the chamber 28 to permit the disinfecting liquid in the valve compartment 70 34 to flow into said chamber. The liquid which enters the chamber 28 reenters the tube 29 below the partition 33 through openings 37 therein and thence flows through said valve-tube and a connecting drainage 75 tube 38 into a pan 39 in the bottom of the case 6. The pan 39 has its top open to the interior of the case 6 so that the fumes rising from the disinfecting material in the pan will fill the case 6 and have contact with the 80 face of the toilet seat 3 when disposed within the opening 7, as the closure plate 12 is then in open position to permit the free 85 passage of fumes into the opening 7 and around the face portion of the seat.

90 The means employed, in the present instance, for raising the valve-tube 29 to permit the entry of a charge of disinfecting material into the compartment 34 thereof, consists in extending the upper end of the 95 control-rod 18 through a side extension of the valve-tube collar 32 and providing a fixed collar 40 on the control rod in position to coact with the collar 32 to raise it and the valve-tube 29 against the tension of the 100 spring 31 when the control-rod is raised. The upper end of the control-rod 18 is shown as working through a guide 41, which is fixed to the lower end portion of the tube 27. It is thus evident that the plate 12 will 105 be moved to close the openings 7, and the valve-tube 29 will be raised to place its charge receiving compartment 34 into communication with the interior of the container 23 when the toilet-seat 3 is lowered, and 110 while it remains in lowered position, due to the finger 20 on the hinge member 4 of the seat coacting with the finger 21 on the lower end of the control-rod 18; and that the plate 12 will be moved to open position and 115 the valve-tube 29 lowered to seating position when the seat is raised, thus permitting the charge of disinfecting material in the compartment 34 of the valve to flow into the pan 39 to freshen the disinfecting material therein. A drainage tube 42 extends from the pan 39 a desired distance above its bottom and into the bowl 1 to permit the disinfecting liquid when it has reached a predetermined height in the pan 39 to flow therefrom 120 into the closet bowl.

125 A stem 43 projects upward from the upper end of the valve tube 29 into the container 23 and through a vent opening 44 in the upper end thereof, said stem being pro- 130

vided without the container with a valve member 45, which closes the vent opening 44 when the valve is in lowered position.

The case 6 is shown, in the present instance, as being carried by a plate 46, which is mounted on the rear portion of the closet bowl 1 and has a portion 46' extending over the rim portion of said bowl and removably secured thereto by a plurality of spring clips 10 47, which yieldingly engage around the inner marginal edge portion of the bowl, as shown in Fig. 2. It is not necessary, however, to mount the case 6 on a plate of this character as it may be secured alone to an 15 adjacent wall, tank, or other suitable support at the rear of the bowl.

48 designates a dash-pot which is connected to the seat 3 to prevent too rapid movements of the seat.

20 It is apparent that with my improved toilet seat disinfecting means, the seat is automatically raised and disinfected after each use thereof, thus rendering it thoroughly sanitary and antiseptic for each subsequent 25 user.

I wish it understood that my invention is not limited to any specific construction or arrangement of the parts as numerous changes and modifications may be made 30 without departing from the spirit of the invention.

Having thus described my invention, what I claim as new, and desire to secure by Letters Patent, is—

35 1. The combination with a toilet seat, of a disinfecting case having an opening for receiving the usable face of said seat when moved from lowered position, means operable to open and close said case opening, and 40 means operable to control the movements of said first means and to permit the discharge of a quantity of disinfecting material into said case.

2. The combination with a movable toilet 45 seat, of a case having an opening for receiving the usable face of the seat when moved from usable position, means operable to open and close said opening, and means operable by movements of the seat to control 50 the movements of said first means to permit a quantity of disinfecting material to enter the case.

3. The combination with a movable toilet seat, of a case having an opening for receiving the usable face of the seat when moved from usable position, means operable to open and close said opening to the interior of the case, and means automatically operable by movements of the seat to control the 60 movements of said first means and to permit the discharge of a quantity of disinfecting material into said case, the fumes of which are intended to disinfect the seat face.

4. The combination with a toilet seat 65 which is automatically movable from low-

ered to raised position when pressure is removed therefrom, of a disinfecting case having an opening for receiving the seat when raised, and mechanism automatically operable by movements of the seat to open and close said opening to the interior of the receptacle and to discharge a quantity of disinfecting material into the case.

5. The combination with a movable toilet seat, of a container for a disinfecting material, a tube extending downward from said container and having an enlargement forming a chamber, a valve tube mounted for longitudinal movements in said tube and having an upper measuring compartment, 75 said valve-tube having inlet and outlet openings for said measuring compartment and having openings below said measuring compartment, the outlet openings from said measuring compartment and the openings 80 below said compartment being in register with said tube chamber when the valve-tube is in normal position, and said inlet openings being open to the interior of the container and said outlet openings being closed to said 85 tube chamber when the valve-tube is moved from normal position, and means operable by movements of the toilet seat to control the movements of said valve-tube, said valve-tube having its lower end portion in communication with the interior of the case to 90 permit the discharge of a quantity of disinfecting material therein.

6. The combination with a movable seat, of a disinfecting case having an opening for 100 receiving the usable face of the seat when moved from usable position, a closure member for said opening, means urging an opening movement of said member, and means operable by a lowering of the seat to move 105 said member into position to close said opening.

7. The combination with a movable toilet seat, of a disinfecting case having an opening for receiving the usable face of the seat 110 when moved from usable position, a closure member mounted for forward and backward movements within the case, means urging an opening movement of said member, and means operable by a lowering of the seat 115 to effect a yielding seating of said member to close said opening.

8. The combination with a movable toilet seat, of a disinfecting case having an opening for receiving the usable face of the seat 120 when the seat is raised from usable position, a closure member for said opening, means urging an opening movement of said member, a receptacle for a disinfecting material, and means operable by predetermined 125 movements of the seat to move said closure member into position to close said opening and to permit a quantity of disinfecting material to enter said case.

9. The combination with a movable toilet 130

seat, of a disinfecting case having an opening for receiving the usable face of the seat when raised from usable position, a closure member mounted within the case for closing said opening, means urging an opening movement of said closure member, a receptacle for a disinfecting material, a valve for said receptacle, a vertically reciprocatory rod having connection with said valve and 10 with said closure member and operable by the seat during predetermined movements thereof to effect a movement of said closure

member to close said opening and a movement of said valve to permit a quantity of disinfecting material to enter said case 15 from the receptacle.

In testimony whereof, I have hereunto signed my name to this specification in the presence of two subscribing witnesses.

ROBERT DAVID MAYO.
